UNITED STATES PATENT OFFICE.

JOHN B. SANBORN, OF EVANSTON, ILLINOIS.

DISPLAY CONTAINER FOR SEPARABLE DEVICES.

Application filed January 18, 1923. Serial No. 613,348.

To all whom it may concern:

Be it known that I, JOHN B. SANBORN, a citizen of the United States, residing at Evanston, in the county of Cook and State of Illinois, have invented new and useful Improvements in Display Containers for Separable Devices, of which the following is a full, clear, concise, and exact description, reference being had to the accompanying drawing, forming a part of this specification.

This invention relates to display containers for separable devices.

The invention has among its objects to provide an improved display container for separable devices which is of simple and inexpensive construction and which serves to securely restrain the devices therewithin against removal and to expose relatively large portions thereof for display.

Another object is to provide a container of the aforesaid character adapted to be constructed of relatively light cardboard or other sheet material.

Another object is to provide a container of the aforesaid character adapted to receive a plurality of articles and to hold parts associated with each of the articles against separation therefrom.

Various other objects and advantages of the invention will hereinafter appear.

The accompanying drawing illustrates an embodiment of the invention which will now be described, it being understood that the embodiment illustrated is susceptible of modification without departing from the scope of the appended claims.

In the drawing,

Fig. 1 is a perspective view of a container embodying the invention;

Fig. 2 is a side elevational view of the articles which the container shown in Fig. 1 is designed to receive;

Fig. 3 is a front elevational view of the container with the articles therein; and

Fig. 4 is a sectional view on line 4—4 of Fig. 3.

The container shown in Fig. 1 is of the folio type and includes leaves 1 and 2 for receiving a plurality of separable devices therebetween. Each of the leaves of the folio is perforated to receive portions of the devices for display thereof, the perforations being shaped to suit the contour of the devices. More specifically, the container illustrated, is designed for receiving knobs 3 and

4, shown in Fig. 2, such knobs being of the character disclosed in my copending application, Serial No. 555,705, filed April 20, 1922. Knob 3 is of larger dimensions than knob 4 and each of said knobs is provided with a central recess for receiving an attaching rivet 5. In marketing such knobs it is desirable to maintain the same and their attaching rivets against separation and for this purpose each of the leaves 1 and 2 of the folio is provided with spaced openings 6 and 7, the openings of leaf 1 being arranged to register with the openings of leaf 2. The openings 6 and 7 are of substantially the same contour as the knobs 3 and 4 respectively, and as shown in Fig. 3 the cross sectional area of said openings is slightly less than the cross sectional area of knobs 3 and 4 respectively. Openings 6 and 7 are arranged to receive knobs 3 and 4 in an inverted relation and the space between said openings is less than the length of either of rivets 5. It is thus apparent that when the knobs 3 and 4 and their associated rivets are held between the leaves 1 and 2 of the folio as shown in Fig. 3, said knobs will be securely held within the folio in a relation to prevent removal of their associated attaching rivets 5. Further it should be noted that upon closure of leaves 1 and 2 of the folio the portions of the leaves between openings 6 and 7 serve to engage the heads of the rivets 5 on opposite sides thereof to support the same as shown in Fig. 4.

Leaves 1 and 2 of the folio can be secured together by any suitable means, such as wire clips 8. As shown in Figs. 3 and 4 the clips are arranged on opposite sides of the knobs and above and below the same, and each comprises a U-shaped wire inserted through the leaves of the container and having its extremities bent inwardly to secure the same.

It is apparent that the container illustrated need not necessarily be of folio form and that the same can be designed for receiving any desired number of articles. Further it is apparent that the same can be designed to receive other types of articles than those shown in the drawing.

I claim:

1. A display container for a plurality of devices each consisting of loosely interfitted and separable parts, which comprises a pair of perforated sheets to receive therebetween a number of said devices and to permit a

part of each device to project therethrough for display and support thereof, said sheets having their perforations so arranged that the several devices positioned therein cooperate to restrain their respective unsupported parts against displacement from the container.

2. A display container for separable devices each having a removable part fitted thereinto, comprising a pair of sheets for receiving a plurality of said devices therebetween each of said sheets being provided with openings for receiving portions of such devices, for display thereof, in a relation to restrain said devices and their removable parts against removal from said container.

3. A display container for a plurality of articles each having a separable part fitted thereinto, comprising a pair of leaves for receiving said articles therebetween with the separable parts in opposite relation, said leaves being provided with spaced openings to receive portions of said articles for display thereof in such relation, the portions of said leaves between said openings serving to restrain said separable parts against removal from said container.

4. A display container for a plurality of articles each having an associated separable part loosely inserted in a recess therein, comprising a pair of sheets for receiving the temporarily assembled articles therebetween, said sheets being perforated to receive portions of said articles for display thereof in a relation whereby said separable parts mutually restrain each other against removal from said container, and means for clamping said sheets about said articles.

5. A display container for a plurality of knobs each having an associated rivet loosely inserted in a recess therein, comprising a pair of sheets for receiving said knobs and associated rivets therebetween, said sheets having openings therein for displaying portions of said knobs and for holding the same in opposed relation to each other to prevent removal of said rivets from the recesses therein.

6. A display container for a plurality of knobs each having an associated rivet loosely inserted in a recess therein, comprising a

folded sheet for receiving said knobs between the folds thereof, said folds having pairs of registering openings therein for displaying opposite sides of the respective knobs and for holding the same in a relation to prevent removal of said rivets from the recesses therein, the portions of said folds between said openings being adapted to engage said rivets on opposite sides to support the same within said container, and means for holding said sheet in folded position.

7. A display container for a plurality of knobs or the like each having the shank of a headed member loosely inserted in a recess therein, comprising sheets of cardboard or the like for receiving said knobs therebetween with the heads of said members in abutting relation, said sheets having openings therein for displaying said knobs and arranged to hold the same in the aforementioned relation to prevent removal of said members from the recesses in said knobs.

8. A display container for a plurality of knobs or the like each having a headed rivet loosely inserted in a recess therein, comprising a folded sheet of relatively stiff material for receiving said knobs therebetween with the heads of said rivets in abutting relation, said sheet having openings with a contour similar to but smaller than the largest cross sectional area of the respective knobs for displaying portions thereof and for holding the knobs in a relation to prevent accidental removal of said rivets from said recesses, and fastening means requiring destruction of said container to permit removal of the contained articles.

9. A display container for combined knobs and attaching means, comprising a folded card having registering openings of smaller size than said knobs to receive the same with the attaching means thereof in abutting relation, and permanent fastening means requiring destruction of said container to permit removal of the contained articles.

In witness whereof, I have hereunto subscribed my name.

JOHN B. SANBORN.
